Inventor:

DANIEL S. EARLY, OF HUMMELSTOWN, PENNSYLVANIA.

Letters Patent No. 83,269, dated October 20, 1868.

IMPROVEMENT IN BUGGY-TOP FASTENING.

The Schedule referred to in these Letters Patent and making part of the same.

To all whom it may concern:

Be it known that I, DANIEL S. EARLY, of Hummelstown, in the county of Dauphin, and State of Pennsylvania, have invented a new and improved Buggy-Top Fastening; and I do hereby declare that the following is a full, clear, and exact description of the construction and operation of the same, reference being had to the accompanying drawings, making a part of this specification, in which—

Figure 1 is a front view of the seat and fastening.

Figure 2 is a side view of the seat, showing an end view of the fastening.

Figure 3 is a vertical section through the line $x x$ of fig. 2.

The object of this invention is to provide a simple and cheap device for securely fastening the top of a buggy to the seat, and so operating, that, by simply throwing down or up a hinge-joint in the fastening-rod, it will instantaneously lock the top to the seat, or loose it therefrom.

In the drawings, A represents the body of the carriage-seat B, the lower part of the frame of the buggy-top, and C C the iron-braces and standards attached to the part B, and resting upon the seat A, when the top is in position, being provided with hooks, c c, which engage under a plate, e, attached to the side of the seat, and hold the forward ends of the parts C C in connection with the seat. The rear portion of the parts C C is connected to the rear upper edge of the seat by means of two pins, p p, projecting downward from the parts C C, which enter eyes in a curved plate or lug, D, projecting upward and backward from the rear edge of the seat.

In connection with the devices above described, I employ a rod, M, jointed at m, and provided with an arm, n, at each end, which enters a socket or eye, o, on the standard C. The ends of the rod are forked, and when the joint is pressed down by hand till the rod is straightened, as shown in fig. 1, the forks m' m' embrace the edges of the lugs D D, and prevent the parts B and C, and the top connected to them, from being detached from the seat. But by simply throwing up the joint m, the forks are withdrawn from the lugs, and, by lifting the back, B, till the pins p p are disengaged from the lugs, and then pushing the top forward till the hooks c c are disengaged from the plates e, the parts B and C are disconnected from the seat, and can be at once removed. The whole operation of locking or unlocking the top and seat is but the work of an instant, being performed simply by depressing or raising the joint m. When locked, no amount of vibration, and no rude shock to the carriage, can unlock the device.

Having thus described my invention,

What I claim as new, and desire to secure by Letters Patent, is—

The jointed bars M, in combination with the arm n n and sockets o o, as and for the purpose described.

To the above specification of my improvement, I have signed my hand, this 10th day of August, 1868.

DANIEL S. EARLY
